METHOD OF AND MEANS FOR MAKING
FLEXIBLE POCKET RECEPTACLESDouglas J. Broughton, Springfield, Mass., assignor
to Buxton, Incorporated, Springfield, Mass., a
corporation of Massachusetts

Application April 11, 1947, Serial No. 740,860

4 Claims. (Cl. 154—41)

1

This invention relates to an improvement in flexible pocket receptacles of the type having a transverse center line of fold about which one part is folded on the other, the parts being held in folded or closed relation by a slide fastener extending along the mating edges, and to the method and means of making it. More particularly it relates to billfolds, pass cases and the like, of the indicated construction in which varying quantities of bills, cards and the like are carried.

One object of the invention is to provide a receptacle of the above character in which the contents, frequently in the form of loosely arranged cards or the like, are prevented or restrained from interfering with the operation of the slide fastener.

In prior constructions the slide fastener when closed tends to draw the flexible tapes, by which the fastener members are connected to the relatively stiff cover sections, inwardly between the edges of the cover, this tendency being particularly pronounced at the corners of the receptacle. This tendency not only detracts from the appearance of the receptacle but greatly increases the chances of interference of the contents with the closing of the slide fastener members. It is a further object of my invention to prevent or minimize this inward bending of the tapes, thus affording increased assurance that the contents of the receptacle will not be damaged by, or interfere with, the operation of the slide fastener, and further to provide a receptacle of enhanced appearance and one which may be slipped easily into a pocket.

A further object is to provide a method and means by which the slide fastener may be assembled with the cover, and the other elements of the receptacle, in the relation, and with the precision, essential to the most advantageous operation of the parts and with a minimum requirement of time and skill in accomplishing the work of assembly.

Other and further objects and advantages of the invention will be made apparent in the following specification and claims.

In the accompanying drawings:

Fig. 1 shows a front view of a billfold embodying the invention, in open position; parts being broken away;

Fig. 2 is a front view of the billfold of Fig. 1, closed and with slide fastener parts in edge securing position;

Fig. 3 is an edge view looking from the bottom in Fig. 2;

2

Fig. 4 is an edge view looking from the right in Fig. 3;

Fig. 5 is an edge view looking from the bottom in Fig. 1;

Fig. 6 is a plan view of the slide fastener with the parts interlocked, the web portion being adhesively prepared;

Fig. 7 is a plan view showing the manner of initially applying the slide fastener to the inner face of the cover of the receptacle;

Fig. 8 is a view similar to Fig. 7 but showing the cover placed upon a fastener-positioning and assembly device, with the fastener elements separated;

Fig. 9 is a view similar to Fig. 8 but showing the fastener members inserted in the positioning groove of the device, portions of the tapes being folded onto the inner face of the cover;

Fig. 10 is a view looking from the lower edge of Fig. 9;

Fig. 11 is a plan view of the completed assembly of parts on the device, portions being broken away;

Fig. 12 is a plan view of the assembly device;

Fig. 13 is an edge view of the assembly device looking from the bottom in Fig. 11;

Fig. 14 is an end edge view of the assembly device; and

Fig. 15 is a detail perspective view showing a clamping structure.

Referring to Figs. 1 to 5 inclusive the receptacle is shown as comprising a cover member 1 and a liner 2 between the superposed edge portions of which the inner edge portions of the tape members 3 of a slide fastener are secured by stitching 4. The tape members 3 are provided on their free edges with interengaging elements on teeth 5 which are brought into and out of engagement by a slider member 6 in the usual and well-known manner. The slide fastener illustrated is of the usual commercial type and further description of it is therefore unnecessary.

The cover member 1 and liner 2 are substantially co-extensive and are formed flat and tend to position themselves normally in a plane, as shown in Figs. 1 and 5, when the receptacle is open. The fastener members 5 however are not spaced a uniform distance outwardly from the cover and liner around the peripheral portions of the end sections of the receptacle. At and adjacent the corner portions, which are rounded, the transverse width of the connecting tapes is decreased with the result that at the corners and adjacent thereto, the teeth 5 of the fastener are

50 spaced a uniform distance outwardly from the cover and liner around the peripheral portions of the end sections of the receptacle. At and adjacent the corner portions, which are rounded, the transverse width of the connecting tapes is decreased with the result that at the corners and adjacent thereto, the teeth 5 of the fastener are

spaced nearer the edge of the cover, the width of the highly flexible tape portions which connect the teeth to the cover progressively narrowing as indicated at 7. This narrowing is preferably carried the full length of the end edges (Fig. 4).

The cover is preferably formed of leather or similar material which is stiffly flexible and, as previously mentioned, is formed flat to normally lie in a plane. When the end sections 8 are folded one over the other to close the receptacle the end sections initially swing flatly into spaced planes with their free edges in spaced coincidence. When the slide fastener elements 5 are brought into interengagement by operation of the slider 6 the narrowing of the tape connections at and adjacent the corners and along the end edges cause the portions of the cover to which the narrowed tape portions are attached to be drawn toward each other and out of their normal planes, against the bending resistance of the cover, with the result that the narrow portion of the tapes are placed under increased transverse tension. As shown the narrowing of the tape is carried across the free ends of the cover sections from corner to corner, but it will be understood that the narrowing may be confined to the corner portions or extended, as found desirable to impose transverse tension to the tapes where needed.

This arrangement, by which the tapes at the corner portions, at least, are placed under increased tension and the adjacent edges of the cover portion are bent closer together, has many advantages over prior constructions and overcomes the several difficulties which have heretofore prevented a more general use of this type of receptacle. Because of the narrowing of the connecting tapes at and adjacent the corners and the imposition of greater transverse tension at these portions the tendency of the fastener members to be drawn inwardly beneath and between the edges of the cover is resisted and the fastener members are kept away from the contents of the receptacle. Moreover, as the fastener elements are brought into engagement, the increasing pressure imposed by the cover sections on the contents tends to prevent displacement of loose cards or the like in the receptacle during the fastening operation, further guarding against interference with the interengagement of the fastener members by the contacts and resulting damage to the latter by the fastener teeth. The attractiveness of the appearance of the receptacle is greatly enhanced and the receptacle is more easily insertable in the pocket since the thinner corners or edges find their way more readily into a pocket opening and between papers or other articles which may be already positioned in the pocket.

In order to realize the maximum efficiency of operation and attain the fullest advantage of my novel construction it is essential that the slide fastener be symmetrically applied to the cover so that the transverse folding zone 9 about which the end sections swing is exactly centered and at right angles to the adjacent edges of the cover in order that the edges of the over folded end sections shall coincide when the fastener is closed. Otherwise the receptacle will have an unsightly twisted appearance when the receptacle is closed and a sliding movement will be imparted to the moveable contents as the slide fastener is operated.

In Figs. 6 to 15, I disclose a novel method and device by which my improved receptacle can be

constructed to secure its maximum benefits.

As shown in Fig. 6 the extended ends and the edge portions of the tapes 3 of the slide fastener, the fastener teeth being in engagement, are first coated on their outer face with a suitable adhesive such as a rubber cement, as indicated at 10. The edge portions of the inner face of the cover 1 are also coated with cement as at 11. With the fastener teeth still engaged the cemented faces of the extended end portions 12 and 13 of the tapes are stuck to the inner face of the cover, the intermediate portion of the closed fastener forming a free loop above the inner face of the cover as shown in Fig. 7. In this manner the ends of the slide fastener may be very accurately positioned on the transverse centerline of the cover and the tapes are positioned and held in the relation to each other conforming to the closed position of the fastener members.

After the ends of the tape have been secured in position as described, the slide fastener is opened, as shown in Fig. 8, and the cover is placed on the top of an assembly device generally indicated at 14. This device comprises a plate or block 15 mounted on a suitable base or supporting member 16.

As perhaps best shown in Figs. 12, 13 and 14 the peripheral faces of the block 15 which are at right angles to the surface of the block are formed with grooves 17. The upper surface of the block lies in a plane and conforms in size and shape to the cover 1 of the receptacle being made. The grooves 17 open to the surface of the blocks at points equally spaced from, and on opposite sides of, the transverse centerline of the surface of the block and of the cover placed thereon, as indicated at 18 and 19, this spacing conforming to the desired position of the fastener teeth 5 at the ends of the folding zone of the cover when the cover is unfolded and flat with the end sections 8 lying in a common plane. The block is recessed at 20 to accommodate the slider 6 of the fastener and the terminal openings 19 lie on the curve of this recess.

The depth and height of the grooves 17 conform substantially to the thickness and height of the teeth of the fastener the extension of the lower shoulder 21 of the groove (Figs. 13 and 14) preferably being at least the full thickness of the teeth while the extension of the upper shoulder 22 is slightly less to accommodate the thickness of the tapes, that is the depth of the grooves is at least equal to the extension of the interengaging teeth from the surface of the tapes, and the height of the groove is at least equal to the height of the teeth.

The spacing of the upper edge of the grooves from the face of block 15 accurately determines the width of tape between the teeth of the fastener and the edges of the cover in the finished product as will be later more fully explained.

With parts on the block as shown in Fig. 8, the teeth of the fastener are seated in the grooves 17 as shown in Figs. 9 and 10 and thereby held in spaced relation from the edges of the cover. The length of the grooves 17 correspond closely to the length of the series of teeth 5 carried by the tapes, and the teeth, once seated in the groove are held therein by the tension of the tapes. While the interengageable teeth members are held by the grooves the upstanding cemented edges 10 are snugly folded onto the cemented edge portions 11 of the cover as illustrated at the right of the latter figures, the tapes being worked or crimped down around the

corners as indicated at 23, except adjacent the ends 12.

After the tapes have thus been secured around the edges, the ends 12 of the tapes are pulled free from the cover, (the nature of the rubber cement permits this to be done) and repositioned in crossed formation as shown in Fig. 11, reducing the crimping needed at these points and giving a better alignment to the slider teeth at the adjacent ends of the grooves 17.

The liner sheet 2 is next cemented over the folded edge portions of the tapes and on the inner face of the cover sheet.

The parts needed to make up the inner elements of the receptacle are next cemented in position on the liner. As shown these comprise two spaced end section wall members 24 each having a flap member 25 extending from its upper edge and folded downwardly between the member 24 to which it is attached and the liner, and two pocket forming members 26 superposed one on each of the end section wall members 25. The flaps 25 are each formed with a slit 27 (Figs. 1 and 11).

The members 24, 25 and 26 are cemented to the liner and each other only along their outer end edges and along the bottom edges of members 24 and 26. The interengageable members 5 are now released from the grooves 17, the assembly is removed from the block and the single line of stitching 4 is run around the edge of the case as shown in Fig. 1 to permanently secure the edge portions of the cover, tapes, liner and inner wall members together. An intermediate wall member 28, having its end portions inserted between members 24 and flaps 25 completes the wall assembly, the member 28 being formed with extensions 29 which are inserted through slits 27 as shown at the left in Fig. 1, to permit the member 28 a limited longitudinal movement. The tapes 3 with their fastener teeth 5 are now tuned upwardly as shown in Fig. 5 to reverse their position in relation to the surfaces of the cover and bring them into position for operation of the slide fastener.

As is apparent from Figs. 10, 13 and 14 the spacing of grooves 17 from the top of the block varies, being closest to the top of the block adjacent the corners and across the end. This spacing determines the spacing of the fastener teeth from the edge of the cover and with the teeth snugly seated in the grooves 17 during the folding down and cementing of the tapes to the cover, as previously described, the fastener members are very accurately applied and secured in the position to effect the desired drawing together of the corner and end portions of the cover as previously described. The assembly is effected much more rapidly and with far greater accuracy than would be possible if the tapes were to be applied solely by eye.

The tension of the tape and the engagement of the interengaging elements 5 in the groove 17 is normally sufficient to hold the fastener elements in position but if desired spring clamp means such as are shown at 30 in Fig. 15 may be associated with the block 15.

I claim:

1. The method of assembling a slide fastener with the cover of a flexible pocket receptacle which comprises, cementing the outer face of the extending end portions of the tapes of a closed slide fastener to the inner face of a shaped cover sheet at opposite ends of the transverse centerline of the cover sheet with the adjacent

ends of the tapes on opposite sides of said line and with the ends of the row of interengaged elements of the fastener accurately aligned with said line, opening the fastener, positioning each tape around the periphery of the adjacent half of the cover with the interengageable elements carried thereby positioned below and spaced from the edges of the cover and with the free edges of the tapes extending upwardly above the inner face of the cover, holding the interengageable elements fixed in said spaced relation from the edges of the cover, folding the upstanding edge portions of the tapes onto the inner face of the cover and cementing said portions to said face while the interengageable elements are so held.

2. The method of assembling a slide fastener with the cover of a flexible pocket receptacle which comprises, adhesively coating the edge portions of the inner face of a shaped cover sheet, adhesively coating the end extensions and the edge portions of the outer face of the tape members of a closed slide fastener, securing said end extensions to the inner face of the cover sheet at opposite ends of the transverse center line of said sheet with the adjacent ends of the tapes positioned on opposite sides of said center line and with the ends of the row of interengaged elements of the closed fastener accurately aligned with said line, opening the slide fastener, positioning the cover sheet on a support having a plane surface with the inner surface of said sheet uppermost, positioning the portion of each tape intermediate its ends around the periphery of the adjacent half of the cover sheet with the interengageable elements carried by the tapes positioned below and spaced from the edges of the cover sheet and with the free edges of the tapes extending upwardly above the inner face of said sheet, holding the interengageable elements fixed in said spaced relation to the surface of said support, the said elements which underlie the corner and end edge portions of the cover sheet being positioned closer to said surface than at the remaining edge portions, and folding the upstanding edge portions of the tapes over onto the cemented edge portions of the cover sheet while the interengageable fastener elements are so held.

3. A device for assembling a slide fastener with the cover of a flexible pocket receptacle which comprises, a block having a plane surface shaped to conform to the shape of the sheet forming the cover of the receptacle, said block having a recess at one end of its transverse center line to receive the slider of the fastener and having a groove formed around the periphery of each end half thereof, the respective ends of said grooves opening to the surface of the block on opposite sides of said transverse center line, the upper shoulders of said grooves being spaced from the upper surface of the block a distance substantially equal to the desired spacing of the interengaging elements of the slide fastener from the edge of the cover in the finished receptacle, the height of the grooves being at least equal to the height of said elements and the depth of said grooves being at least equal to the extension of said elements from the tapes by which they are carried.

4. A device for assembling a slide fastener with the cover of a flexible pocket receptacle which comprises, a block having a plane surface shaped to conform to the shape of the sheet forming the cover of the receptacle, said block having a

recess at one end of its transverse center line of fold to receive the slider of the fastener and having a groove formed around the periphery of each end half thereof, the respective ends of said grooves opening to the surface of the block on opposite sides of said transverse center line, the upper edges of said groove being spaced from the upper surface of the block, said spacing being less at and adjacent the corners of the end halves than at the longitudinal sides of the **10** halves.

DOUGLAS J. BROUGHTON.
